[57] CLAIM

The ornamental design for a combined dispensing container and cap, substantially as shown and described.

DESCRIPTION

FIG. 1 is a front elevational view of a combined dispensing container and cap showing our new design, the rear being identical to the front;

FIG. 2 is a side elevational view looking from the right side, the left side being identical to the right;

FIG. 3 is a top plan view thereof; and

FIG. 4 is a bottom plan view.

FIG. 3

FIG. 2

FIG. 1

FIG. 4
